Specification for Design.

Patented July 20, 1920.

Application filed January 24, 1920. Serial No. 353,888. Term of patent 14 years.

To all whom it may concern:

Be it known that I, ALLYN R. COOPER, a citizen of the United States of America, and resident of Marshalltown, Marshall county, Iowa, have invented a new, original, and ornamental Design for a Handle for Muffler-Valves, of which the following is a specification.

My design is illustrated by the accompanying drawing in which—

Figure 1 is a side view, Fig. 2 an edge view, Fig. 3 an opposite side view and Fig. 4 a cross-section on the indicated line 4—4 of Fig. 2, of a handle for muffler valves embodying my design.

I claim—

The ornamental design for a handle for muffler valves, as shown.

ALLYN R. COOPER.
